ABSTRACT

A metal blank is contoured for attachment to a substantially cylindrical container edge and the forming of a protective covering on said container edge.

5 Claims, 4 Drawing Figures

PATENTED JAN 25 1972

3,636,608

FIG. 2

INVENTOR.
J.K. THOMPSON

BY Young + Quigg

ATTORNEYS

CONTAINER PROTECTIVE EDGE COMPONENT

This invention relates to a container blank for forming a protective edge. In another aspect, this invention relates to a contoured metal blank for attachment to and forming a protective edge for the end of a cylindrical container.

Containers, particularly containers formed of paperboard and the like for holding articles that are intermittently removed therefrom, often have an edge that frays and/or tears during the repeated opening of a lid of the container and removal of articles contained therein. Where the edge of said container is relatively thin, a person handling the container might also be cut while manipulating the container. Another aspect of these previously used containers is that where the container is utilized for packaging food, such as potato chips and the like, dirt and germs can more readily accumulate in a frayed or torn edge and particles of the container's frayed edge can separate, fall into the container, and contaminate the food contained therein.

It is therefore an object of this invention to provide a contoured blank for forming a protective edge on a container. Another object of this invention is to provide a contoured metal blank for attachment to and forming a protective edge for a substantially cylindrically shaped end of a container. Yet another object of this invention is to provide a contoured metal blank for attachment to and forming a protective edge for a container of the above-described type to prevent said edge from fraying and tearing.

Other aspects, objects, and advantages of the present invention will become apparent from a study of the disclosure, the appended claims, and the drawing.

The drawings are views of the contoured blank of this invention.

FIG. 1 is an axonometric view of the contoured blank,

FIG. 2 is an end view of another embodiment of the contoured blank,

FIG. 3 is a sectional view of the contoured blank of FIG. 1 taken along line 3-3, and

FIG. 4 is an axonometric view of yet another embodiment of the contoured blank.

Referring to FIG. 1, the contoured blank 2 is formed from a substantially rectangularly shaped elongated strip of material that is twice folded longitudinally at spaced-apart locations to form first, second, and third portions 4, 6, 8. The first fold 10 defines adjacent sides of a first and second portions 4, 6 of the contoured blank 2 and the second fold 12 defines adjacent sides of the second and third portions 6, 8 of the contoured blank 2. Each portion 4, 6, 8 of the contoured blank 2 has a substantially rectangular configuration.

Referring to FIGS. 2 and 3, the second portion 2 is folded to form an angle of about 90° relative to the first portion 4 and the third portion 8 is folded toward the first portion 4 to form an angle of about 120° relative to the second portion 6 in the formed condition of the contoured blank 2.

In order to resist damage to the edge of the container, be easily formed and subsequently attached to the container, and be capable of being relatively sanitary, it is preferred that the contoured blank 2 be formed of metal such as steel, aluminum, copper, brass, and the like. In order to prevent detachment of the contoured blank 2 from the container and prevent lateral movement relative to the container while maintaining the amount of material utilized to a minimum, the width of the first portion 4 should be about two times longer than the width of the second portion 6 and the width of the second portion 6 about two times longer than the width of the third portion 8 of the contoured blank 2. Since the contoured blank 2 of this invention comes in contact with a person's hands, it is important that first and second surfaces 14, 16 of the folds 10, 12 be relatively blunt in order to eliminate sharp edges upon which a person might be injured. For this reason, it is preferred that the radius of the first and second folds 10, 12 be at least 0.02 inch. Folds having a smaller radius have been found to be excessively sharp.

In forming a contoured blank 2 for attachment to and the forming of a protective edge for a container having a substan-

tially cylindrical shape with a circumference of about 30 inches, for example, it has been found that a minimum of material is utilized and the blank 2 is capable of being securely attached to the cylinder if the contoured blank 2 is formed of metal, has a first portion 4-width excluding the radiused fold of about 0.30 inch, a second portion 6-width excluding the radiused folds of about 0.14 inch, a third portion 8-width excluding the radiused fold of about 0.16 inch, and each portion has a thickness of about 0.01 inch with the first fold 10 having an inside radius of about 0.02 inch and the second fold 12 having an inside radius of about 0.078 inch with the angle between the first and second portions 4, 6 being about 90° and the angle between the second and third portions 6, 8 being about 120° as described above.

15 Since the contoured blank 2 of this invention is generally attached to the container by machinery, it is preferred for use in some machines that at least one protrusion 18 (better seen in FIG. 3) be formed on the blank 2 with said protrusion 18 extending laterally from the plane of an outer surface 20 of said third portion 8 at an opposed direction from the general direction of the first portion 4 of the blank 2 relative to said third portion 8. This protrusion 18 should have a length sufficient to prevent contact of the third portions 8 of adjacent 20 blanks when said blanks are stacked one upon the other in, for example, a blank reservoir of a blank attaching machine. By preventing contact of the adjacent third portions 8, as described above, separation of one blank from another and separate feeding of individual blanks intermittently into a blank attaching machine is facilitated. It has been found that if said protrusions are not formed, in some types of blank feeding apparatus the blanks have excessive frictional drag when being moved relative to one another and cause said feeding apparatus to malfunction.

25 35 It should be understood that more than one protrusion can be formed on the blank and said protrusions can be located at other locations so long as they function to slightly separate portions of one blank from an adjacent blank of a stack of blanks. Third portion 8 may have corrugations 22 as illustrated in FIG. 4 to produce the same result.

30 Other modifications and alterations of this invention will become apparent to those skilled in the art from the foregoing discussion, example, and accompanying drawing, and it should be understood that this invention is not to be unduly limited thereto.

40 What is claimed is:

45 1. An end component for attachment to and forming a protective edge for an end of a substantially cylindrical container, comprising:

50 an elongated strip of a length sufficient to pass substantially completely about the end of a container, said strip being twice longitudinally folded at spaced-apart locations to form only first, second and third generally planar portions with each portion having a substantially rectangular configuration, said second portion being folded to form an angle of about 90° relative to the first portion and said third portion being folded toward the first portion to form an angle of about 120° relative to the second portion in the formed condition of the blank.

55 60 2. A blank, as set forth in claim 1, wherein the width of the first portion is about two times larger than the width of the second portion and the width of the second portion is about two times larger than the width of the third portion.

65 3. A blank, as set forth in claim 1, wherein the third portion has at least one protrusion formed thereon extending laterally from an outer surface of said third portion in an opposed direction from the direction of the first portion of the blank relative to said third portion.

70 4. A blank, as set forth in claim 1, wherein the two folds each has an inside radius at least 0.02 inch for forming folded portions having blunt surfaces.

75 5. A blank, as set forth in claim 1, wherein the first portion has a width of about 0.30 inch, the second portion has a width of about 0.14 inch and the third portion has a width of about

0.06 inch, and each portion has a thickness of about 0.01 inch,
a length of about 30 inches and is formed of metal.
